UNITED STATES PATENT OFFICE

GEORGE W. GRADER, OF MARBLEHEAD, MASSACHUSETTS.

SECTOR-LEVER PRESS.

SPECIFICATION forming part of Letters Patent No. 362,953, dated May 17, 1887.

Application filed February 8, 1887. Serial No. 226,949. (No model.)

To all whom it may concern:

Be it known that I, GEORGE W. GRADER, of Marblehead, county of Essex, and State of Massachusetts, have invented an Improvement 5 in Sector-Lever Presses, of which the following description, in connection with the accompanying drawings, is a specification, like letters on the drawings representing like parts.

My invention has for its object to improve 10 the construction of that class of cotton presses known as the "sector-lever" press.

Sector - lever presses as heretofore constructed and known to me have been made with a cylinder supported upon the bed-plate 15 between the hub-journal supports of the sector-levers, the piston-rack of the piston in the said cylinder actuating both sector-levers.

In presses of the class referred to the hub-journals of the sector-levers rest in bearings 20 on columns supported on the ends of the bed-plate.

In sector-lever presses having the supports 25 for the sector hub journals resting on the ends of the bed-plate and the power-cylinder supported at the center of the bed-plate, the reacting pressure of the sector hub-journals comes at the ends of the bed-plate, while the reacting pressure of the power-cylinder is at the center of the bed-plate. When the sector-levers are

30 moved to bring the lifting bed-plate toward the cylinder bed-plate, the leverage of the sector-levers multiplies, and, consequently, in the same ratio, the reacting pressure of the sector hub-journals on the ends of the cylinder bed-plate is multiplied, while the reacting pressure 35 of the power-cylinder remains unchanged or constant, thus subjecting the cylinder bed-plate to a transverse strain, the force of the said strain being directly proportional to the 40 distance of the point of application of the reacting pressure of the sector hub-journals from the center of the cylinder bed-plate, the bed-plate being formed, as it were, into a lever with its fulcrum at the center. In this class of

45 sector-lever presses the cylinder bed-plate is required to be of very great strength, thereby rendering it impracticable to construct a bed-plate with a proper factor of safety for a working-load, such as is now demanded for preparing 50 bales of cotton for shipment by the compressed - bale system, such as described in United States Patent No. 281,490, dated July

17,1883. In accordance with my invention I have transferred the multiplying reacting pressure of the sector-lever hub-journals from the 55 ends to the center of the cylinder bed-plate, and I have accomplished this result by removing the sector-hub-journal supporting columns from the ends to the center of the said bed-plate and placing a power-cylinder at each end 60 thereof. By thus placing the supports for the sector-lever hub-journals in such position on the cylinder bed-plate the downward multiplying reacting pressure of the said sector-lever hub-journals is brought directly over the 65 upward multiplying power of the sector-levers as transmitted to the lifting-bed. It will thus be seen that the multiplying reacting power of the sector hub-journals is transferred to the center of the cylinder bed-plate, while the reacting pressure of the power-cylinder, which is constant, has been transferred from the center to each end of the cylinder bed-plate, thereby relieving the said cylinder bed-plate of all 70 multiplying leverage strain and submitting 75 the same to a compressive crushing strain at the center and directly over the acting power as transmitted by the uplifting movement of the lower bed-plate, consequently permitting the said bed-plate to be made very much 80 lighter.

Another feature of my invention consists in equalizing the working-load of the two pistons by transmitting power from one cylinder to the other, and I effect this result by providing the sector - levers with back gears in 85 mesh with each other.

Still another feature of my invention consists of means for automatically lifting each 90 sector hub-journal off its bearings to permit oil or other lubricant to flow between the hub-journal and its bearing at each downward stroke of the press.

Figure 1 is a front elevation of a sector-lever press embodying my invention. Fig. 2 is 95 a detail showing in end view a hub-journal of a sector-lever supported in its bearings; Fig. 3, a detail in section and elevation showing in section the hub of a sector-lever and its journal-shaft, and in elevation a journal-box 100 broken out to show the lubricating chamber. Fig. 4 shows in elevation and section the mechanism employed to lift the sector hub-journals off their bearings, the part in section showing

the means by which to adjust the upper portion longitudinally to take up the wear upon the sector-levers; Fig. 5, a sectional detail to be referred to, the section being taken on line 5 $x x$, Fig. 3; Fig. 6, a side view of the lifting-arm. Fig. 7 is a top view of one of the cross-heads for supporting the piston-rack, it being broken to show in cross-section the piston-rack, V-slides, and friction-rolls; Fig. 8, a section of Fig. 7 on line $x' x'$, and Fig. 9 is a section of Fig. 7 on the irregular line $y y$.

The upper metallic bed-plate, A, resting, as herein shown, upon columns A', which stand upon a suitable foundation, A'', supports at its 10 opposite ends two cylinders, a a', preferably steam-cylinders, the steam being supplied to and discharged from the said cylinders by pipes and valves. (Not herein shown.)

The cylinders a a' are each open at the top, 20 and are provided with pistons a a⁵, respectively, (see dotted lines, Fig. 1,) the piston a⁴ having a piston-rod, a⁶, made as a rack, and the piston a⁵, a piston-rod, a⁷, also made as a rack, the said piston-racks being held in proper working position by guides, in a manner as will be described.

Each cylinder a a' has bolted to it a cross-head stand, 20, which supports a cross-head, 21, to which are secured adjustable V-slides 30 22, the said V-slides fitting in corresponding V-grooves in the piston-rack to maintain the said piston-rack in its proper working position. (See Fig. 7.)

Each cross-head 21 carries, as herein shown, 35 two adjustable friction-rollers, 23 24, the face of each roller being pressed against the abutting-face of the piston-rack by a compensating spring, 30, which is kept pressed against the outside face of the journal-boxes of each friction-roller by a back plate, 25, and set-screws 40 26, passing through a supporting-bar, 27, (see Fig. 8,) the power of the spring to force the roller against the abutting face of the rack being regulated by the said set-screw. The 45 springs 30 give to the rollers 23 24 a compensating or yielding movement to relieve the friction between the back of the piston-rack and the abutting face of the cross-head.

The construction of the press, so far as pertains to my improvements, is the same on its front and rear sides, and therefore only the parts of the press on one side, as on the front side, (shown in Fig. 1,) need be described, the parts on the rear side performing their functions in identically the same way as those on the front side.

The piston-rack a⁶ is extended beyond the top of the cylinder a, and the teeth of the said piston-rack engage the teeth of a front toothed 60 segment of a sector-lever, B, secured to a shaft, b', having its journals supported in bearings b^x, (see Fig. 3,) resting upon a pillow-block, b⁵, secured to or forming part of a column, B', fastened, as shown, to a saddle, E, secured to 65 the top of the bed-plate A. The teeth on the piston-rack a⁶ engage the teeth b⁵ of a front toothed segment of a sector-lever, B', secured

to a shaft, b⁴, having its journals supported in similar bearings, b^x, resting upon a pillow-block, b⁵, secured to a column, B', fastened to 70 the saddle E, and also to the pedestal B', by the cross-ties b⁶ b⁷, secured together.

The sector-lever B has a journal-shaft, c, to which is attached a lifting-rod, C, also attached at its lower end to a journal-shaft, c', 75 on the lifting bed-plate C', located in a space between the foundations A'', and vertically movable in guides c^x therein, (see dotted lines, Fig. 1,) the said lifting-bed also having a journal-shaft, c², to which is connected one end of 80 the lifting-rod C', the other end of the said lifting-rod being attached to a journal-shaft, c³, on the sector-lever B'.

The sector-levers B B' are respectively provided at their rear side with a segment of 85 toothed gearing, c⁴ c⁵, in mesh with one another.

The press as thus far described may be used either to compress a single bale of cotton or for the recompressing of two or more once- 90 compressed bales into one bale or package, substantially in the manner and for the purpose described in United States Patent No. 281,490, granted to me July 17, 1883.

Let it be supposed that a number of bales of 95 cotton—say from two to eight—have been placed upon the lifting-bed C'. Then the steam or other power is admitted to the cylinders a a' to move the pistons a a⁵ upward. As the pistons a a⁵ are forced upward their racks a⁶ a⁷ turn the sector-levers B B', respectively, in the directions indicated by arrows 23, Fig. 1, the sector-levers being turned in the said directions until the resistance offered by the compressed bales between the cylinder bed-plate and the lifting-bed equals the power of 100 the said pistons plus the accumulated power of the sector-levers. It will thus be seen that the downward multiplying reacting pressure of the sector hub-journals upon their bearings is directly over and opposed to the upward compressing power of the lifting-bed, thus submitting the material of the cylinder bed-plate to a compressive crushing strain instead of a transverse strain, as is the case with 105 sector-lever presses as heretofore constructed.

If it should happen, as the bales of cotton are being compressed between the upper and lower bed-plates, that greater resistance should be offered by the bales at or near either end of 110 the lifting-bed than at the other, then in this case power will be transmitted from one cylinder to the other cylinder through the medium of the toothed segments c⁴ c⁵ on the back of the sector-levers to equalize the working-load of the two piston-racks, consequently 115 obtaining a simultaneous movement of the two pistons.

In order to provide for a more perfect lubrication of the sector hub-journals, the teeth 120 near the lower end of the toothed segment b b⁵ of the sector-levers B B' are respectively engaged by the toothed surface or end d^x of arms d d'. The toothed surface or end d^x of each

arm d d' extends across the sector-lever with which it co-operates, and on opposite sides of the said sector-levers the said arms have uprights d^2 d^3 respectively secured to them, the uprights d^2 on the arm d co-operating with a roller or stud, d^4 , on the sector-lever B , while the uprights d^3 co-operate with a roller or stud, d^5 , on the sector-lever B^2 , for a purpose to be hereinafter set forth.

10 Each arm d d' is provided with a journal-shaft, e^1 , resting in its box e , (see Fig. 4,) supported in a pillow-block, e' , secured, as shown, to the saddle E , and provided with upright guides e^0 for the journal-box, the journal-box resting upon an adjustable wedge, e^3 , the latter being supported by the pillow-block. The wedge e^3 is provided with screws e^4 , (only one being shown,) the said screws having, as shown, two collars, e^5 , supported in a bearing, e^6 , secured to the saddle, the screw e^4 being rotated by the wheel e^7 , but prevented from moving longitudinally by keys e^8 , inserted through openings in the bearing e^6 , there being a key above and below the screw e^4 between the collars e^5 , rotation of the screw moving the wedge e^3 to raise or lower the journal-box e , and thereby the arm d' , as desired.

15 Referring to Figs. 2 and 3, I have shown one pillow-block, as b^2 , detached from its column B' , to more clearly illustrate the method of lubricating the hub-journals of the sector-levers. The bearing f of the shaft b' , as herein shown, has secured to it at its front end a semi-circular plate, f' , extended above the center of 20 the hub-journal. The end of the hub-journal is cut away to form a chamber, f^3 , between it and the plate f' , for the reception of oil or other lubricant. The shaft b' , as herein shown, is provided with a central longitudinal bore, f^4 , 25 communicating with the periphery of the hub-journal by radial passages f^5 , (see Figs. 2 and 3,) the oil or other lubricant in the chamber f^3 flowing into the bore f^4 and through the passages f^5 to the bearings to lubricate the 30 same when the sector-lever hub-journals are raised from their bearings by the arm d , as will be described.

35 Referring to Fig. 1 it will be noticed that as the sector-lever B is moved in the direction of arrow 3 the arm d is moved toward the left, or in direction of arrow 4, until the teeth on the end of the said arm are disengaged from the toothed segment b of the sector-lever, and when thus disengaged the arm d falls by gravity, as 40 herein shown, until a buffer, f^6 , on the said arm strikes a buffer, f^7 , secured to the cylinder a . The arm d' is moved in the opposite direction, as indicated by arrow 5, by the sector-lever B^2 , a buffer, f^8 , on the said arm striking against a buffer, f^9 , secured to the cylinder a' . The arms d d' rest with their buffers bearing against the buffers f^7 f^9 , respectively, during the completion of the upper movement of the sector-levers, and also on the backward 45 movement of the said sector-levers until the rollers d^4 d^5 , attached to the sector-levers B B^2 , respectively, engage the uprights d^2 d^3 , secured

to the said arms, the said rollers on the further backward movement of the sector-levers bringing the teeth on the arms into engagement with the teeth of the toothed segment b b^3 of the sector-levers, and at the completion or final backward movement of the sector-levers the longitudinal axis of each arm will be directly under and in line with the center of the hub-journal 75 of the sector-lever with which it co-operates.

The lengths of the arms d d' are so adjusted by means of the wedges e^3 that when brought into their vertical position the hub-journals of the sector-levers will be automatically raised 80 bodily from off their bearings b^x any desired distance, to permit the oil in the chamber f^3 to flow freely in between the journal and its bearing b^x , and also from the bore f^4 through the passages f^5 to the bearing, the latter in this 85 manner being thoroughly lubricated at each downward stroke of the press.

To prevent the oil escaping from the end of the box next to the sector-lever hub a packing, f^{12} , is wound in a recess between the sector-lever hub and the side of the box of the journal-bearing, as shown in Fig. 3.

When the journal is lifted up from its bearings, as described, it is necessary that provision should be made whereby the cap g of 95 the journal may be raised at the same time, and to be again lowered when the journal is lowered upon its bearing, the cap thus effectively covering the journal at all times. To effect this result the cap g is provided on both 100 sides with a bolting-flange, g' , (see Fig. 5,) which has extended through it at suitable intervals apart collar-bolts g^2 , screwed, as shown, into the pillow-block b^2 . The flange g' about the bolt g^2 is bored out to form a chamber to 105 receive a rubber or other spring, g^3 , provided with a follower, g^4 , the said follower retaining the rubber or other spring in its chamber by the adjustment of the nut g^5 .

When the hub-journal rests upon its bearing, 110 the parts just enumerated occupy the position shown in Fig. 5; but when the journal is raised off its bearing, as described, the cap g is moved upward, the spring g^3 being compressed, and when the journal is lowered again to its bearings the cap g is replaced by its own weight, assisted by the spring.

To obviate jarring of the press the sector-levers at each end are provided with buffers h , 115 preferably of rubber.

I claim—

1. The combination, in a sector-lever press, of the following instrumentalities, viz: a cylinder bed-plate, a lifting bed-plate, sector-levers intermeshing one with the other, two 125 cylinders, means, substantially as described, to operate the said sector-levers, and lifting-rods to transmit the power of the sector-levers to the lifting-bed, the said instrumentalities operating substantially as described.

2. In a sector-lever press, the cylinder bed-plate, two cylinders, one at or near each end thereof, pistons therein, two sector-levers having their journal-supports resting upon the said

bed-plate intermediate of the said cylinders, the lifting bed-plate, and lifting-rods to transmit the power of the sector-levers to the said lifting bed-plate, combined with means, substantially as described, operated by the said pistons to actuate the said sector-levers, whereby the downward reacting pressure of the sector-journals is applied directly over the upward compressing power of the sector-levers, substantially as described.

3. In a sector-lever press, the cylinder bed-plate, two cylinders, one at or near each end thereof, pistons therein, two sector-levers having their journal-supports resting upon the said bed-plate intermediate of the said cylinders and intermeshing one with the other, the lifting bed-plate, and lifting-rods to transmit the power of the sector-levers to the said bed-plate, combined with means, substantially as described, operated by the said pistons to actuate the said sector-levers.

4. In a press, the cylinder bed-plate, two sector-levers geared one with the other and having their journal-bearings supported by the said cylinder bed-plate, the lifting bed-plate, and connecting-rods to connect it operatively with the said sector-levers, combined with two cylinders located at or near the ends of the cylinder bed-plate, pistons therein having toothed piston-rods, and with guides, substantially as described, for the said piston-rods, substantially as set forth.

5. In a sector-lever press, a sector-lever and a bearing for the journal of the said sector-lever, combined with a plate to co-operate with the end of the said journal to form a chamber to contain a lubricant, and with means, substantially as described, co-operating with the said sector-lever to lift the journal from its bearing to permit the lubricant in the said cham-

ber to flow between the said journal and its bearing, substantially as described.

6. In a sector-lever press, a sector-lever, a bearing for the sector-lever journal, and a cap to cover the said journal and provided with a packing, substantially as described, combined with a plate to form with the end of the said journal a chamber to contain a lubricant, and with means, substantially as described, to co-operate with the said sector-lever to lift the journal from its bearing to permit the lubricant in the said chamber to flow between the said journal and its bearing, substantially as described.

7. In a sector-lever press, a sector-lever and a bearing for the sector-lever journal, and a plate to form with the end of the said journal a chamber to contain a lubricant, combined with means, substantially as described, co-operating with the said sector-lever to lift the journal from its bearing to permit the lubricant in the said chamber to flow between the journal and its bearing, and with the packing ^{f¹²}, wound between the sector-lever hub and its journal-bearing, as and for the purpose specified.

8. In a sector-lever press, a toothed sector-lever, a piston-rack co-operating therewith and provided with V-grooves, combined with V-slides fitted to said grooves and with a friction-roller in contact with the said piston-rack, as and for the purpose specified.

In testimony whereof I have signed my name to this specification in the presence of two subscribing witnesses.

GEORGE W. GRADER.
